CLAIM

The ornamental design for a utility knife, as shown and described.

DESCRIPTION

FIG. 1 is a perspective view of a squeeze knife embodying the new design;

FIG. 2 is a right side view thereof.

FIG. 3 is a left side view thereof.

FIG. 4 is a front view thereof.

FIG. 5 is a back view thereof.

FIG. 6 is a top view thereof.

FIG. 7 is a bottom view thereof.

FIG. 8 is a perspective view of the squeeze knife of FIG. 1, showing the design with alternate unclaimed broken line features.

FIG. 9 is a right side view thereof.

FIG. 10 is a left side view thereof.

FIG. 11 is a front view thereof.

FIG. 12 is a back view thereof.

FIG. 13 is a top view thereof; and,

FIG. 14 is a bottom view thereof.

The broken lines depict portions of the utility knife in which the design is embodied that are not considered part of the claimed design.

1 Claim, 10 Drawing Sheets
